UNITED STATES PATENT OFFICE.

JOHN GRANT, OF OMAHA, NEBRASKA.

CONDUCTOR FOR ELECTRIC WIRES.

SPECIFICATION forming part of Letters Patent No. 371,681, dated October 18, 1887.

Application filed February 19, 1887. Serial No. 228,245. (No model.)

To all whom it may concern:

Be it known that I, JOHN GRANT, a citizen of the United States, residing at Omaha, in the county of Douglas, State of Nebraska, 5 have invented certain new and useful Improvements in Underground Electric Conductors, of which the following is a specification, reference being had therein to the accompanying drawings.

10 This invention relates to certain improvements in underground electric conductors; and it has for its objects, first, to provide an improved insulating compound for covering such conductors which will effectually exclude 15 moisture and the leakage of the current consequent thereupon, which will be pliable and, to a certain extent, elastic, so as to bend with the wires without breaking, which will expand and contract with the wires, and which will 20 be comparatively indestructible under the conditions and uses to which it is applied; second, to provide an insulating material which may be readily applied to one or any series of wires as they are laid and stretched in their 25 underground beds, so as to effect perfect insulation, as more fully hereinafter set forth, and, third, to provide improved means for laying the wires in the insulating compound, as more 30 fully hereinafter specified.

35 My invention consists in a composition of rosin with certain petroleum products—such as dead-oil, or the *caput mortuum*, or the comparatively useless portions left after refining crude petroleum—and in some instances with paraffine and naphthaline, the said products being designed to modify the character of the 40 rosin, so as to destroy its brittleness, increase its tenacity, and enhance its insulating properties, by preventing cracking and the infiltration of moisture which would be attendant thereupon.

45 In the accompanying drawings, Figure 1 represents a perspective view showing my improved conduit in course of construction; and Fig. 2, a detached view of one of the sheets, showing the wires partially embedded therein.

In carrying out my invention I first melt the rosin in any desired quantity and in any convenient vessel, and then add the oil thereto

in proper proportion to give the ultimate compound the requisite characteristics. 50

The oil I employ is preferably the dead-oil resulting from the distillation of petroleum, although other petroleum products—such as paraffine-oil, naphthaline, or other like petroleum compounds—may be employed. 55

The proportions of the rosin and the oil may vary greatly, according to circumstances; but for general use where the compound consists of rosin and oil exclusively I have found 60 from twelve to twenty per cent. of oil to rosin to answer well for general purposes, and, where sand, slag, or other silicious or vitreous substance forms part of the compound, from twenty to thirty per cent. of oil. 65

The compound may be applied to the wires singly, so as to coat each individually; but I prefer to form the compound into sheets of suitable dimensions for convenience of transportation and manipulation. Where the sheets 70 are employed, a continuous layer or base of the same is laid in the underground trench and the wires stretched along its surface at properly-spaced intervals. Over the wires, when thus laid, a similar layer is superposed and 75 compressed against the lower layer, embedding the wires between the layers, the nature of the compound being such that the respective sheets coalesce at their junctions, forming impervious and perfectly-insulated coverings for the 80 wires. In some instances the wires may be initially laid in suitable troughs or on forms temporarily laid in the trench, and the compound run in in a fluid state, and after hardening or setting the trough or forms may be 85 removed, leaving the compound to support the wires alone as well as insulate them. The joints between the sheets, when the same are laid, may be filled with the fluid cement and thus hermetically sealed; but this will be unnecessary ordinarily, as the nature of the cement will close the joints, generally, without this extra precaution. As a matter of course, in either case of laying and applying the wires, the trenches after the conduit has been laid 90 are covered up and paved over in the usual manner. 95

Having thus fully described my invention,

what I claim, and desire to secure by Letters Patent, is—

The compound herein described for insulating electric conductors, the same consisting of rosin and petroleum residuum thoroughly mixed, so as to form a semi-plastic mass, substantially as described.

In testimony whereof I affix my signature in presence of two witnesses.

JOHN GRANT.
